CARTON ASSEMBLING MECHANISM

Henry K. Powell, Chicago, Ill., assignor, by
mesne assignments, to President and Directors
of the Manhattan Company, New York, N. Y.,
a corporation of New York, as trustee for Gib-
son Patent Containers, Ltd., a corporation of
New South Wales, Australia.

Application July 16, 1936, Serial No. 90,858

8 Claims. (Cl. 93—55.1)

The present invention relates to mechanism
for assembling elements of cartons or containers
and refers in particular to a device for assembling
the body portion of a fibrous container with a
5 metallic rim member which is interlocked with
the upper edge of the body portion.

In employing flexible fibrous containers for
many purposes such as in the packaging of ice
cream and other frozen commodities, it is desir-
10 able to provide the ends of the body portion of
the container with supporting members such as
metallic rims. In Patent No. 2,009,505, issued
July 30, 1935, is disclosed a container of this type
15 and a mechanism for assembling a bottom rim
member with a body portion in such a manner as
to afford support for the same. In this container,
the bottom of the body portion is inserted in a
metallic rim and expanded to form an interlock,
20 the inner flange of the rim fitting about the bot-
tom edge and extending inwardly in a horizon-
tal manner.

A principal object of the present invention is
the provision of a means for mounting a metallic
25 rim about the top of the body portion of a con-
tainer of the type described, the mechanism being
operable to initially contract the body portion to
get an enlarged edge portion past an inwardly
extending flange of a metallic rim and then to
30 expand the leading edge of the body portion to
position it in a receiving channel.

An additional object of the invention is to pro-
vide a device of the type described having an out-
wardly expansible and inwardly extending guide
35 portion combined with an outwardly expansible
inner guide member.

Still another object of the invention is the pro-
vision of a device for mounting a metallic rim to
an enlarged edge portion of a flexible container,
40 the device including an outer and upper funnel-
shaped member for overriding the upper edge of
the rim member and an inner conical-shaped
guide member.

These and other objects will be evident upon a
consideration of the following specification and
45 by reference to the accompanying drawings, in
which

Fig. 1 is a side view of the device constructed
in accordance with the invention;

Fig. 2 is a top view of the device shown in
50 Fig. 1;

Fig. 3 is an enlarged fragmentary view partly
in section taken along line 3—3 of Fig. 1 and
showing the latch mechanism for maintaining
the jaws of the device in closed position;

55 Fig. 4 is a sectional view taken along line 4—4
of Fig. 2;

Fig. 5 is a bottom plan view taken along line
5—5 of Fig. 4;

Fig. 6 is a fragmentary view showing an initial
60 stage in the operation of the device;

Fig. 7 is a view similar to Fig. 6 and shows an
intermediate stage in the operation of the device;

Fig. 8 is a view similar to Fig. 6 showing a final
stage in the operation of the device; and

Fig. 9 is a cross sectional view, partly broken
away, of a rim member of the type adapted to
5 be assembled by the mechanism shown in the
drawings, together with a container.

As shown in the drawings, the metallic rim
member which it is desired to assemble with the 10
container includes an annular vertical wall 10
having a lower inwardly extending channel por-
tion 11 which consists of an inwardly and up-
wardly turned flange, the upwardly turned por-
tion of which is spaced apart from vertical wall 15
10. The top of the vertical wall 10 is turned over
to form a horizontal inwardly extending flange
12 which is of somewhat less width than the
channel member 11. That is, the upwardly turned
portion of the channel member 11 is spaced from 20
the vertical wall 10 slightly more than the width
of the flange 12. This rim is employed on con-
tainers having an edge portion of increased thick-
ness, such a container being indicated at 13 in
25 Fig. 9, the body portion of the container having
an extra thickness along its edge portion as indi-
cated at 14. This extra thickness may consist of
an annular strip of the same type of material as
the body portion. In most cases it will be found
30 desirable to provide the edge portion with extra
thickness by turning over the edge of the body
portion and adhesively securing it along the side
walls.

The rim and container are assembled in the
form shown in Fig. 8. The vertical wall 10 of 35
the rim has an inside diameter substantially the
same as the outside diameter of the container 13
and strip 14. The flange 12 extends inwardly a
distance which is substantially equal to the width
40 of the strip 14. The height of the vertical wall
10 is substantially the same as the height of the
strip 14. The inside width of the channel mem-
ber 11 is substantially the same as the combined
widths of the strip 14 and the body member 13.
45 It will be seen that when assembled the edge of
the body member is received in the channel 11
thereby limiting the vertical movement of the rim
in one direction and preventing inward move-
ment of the edge of the container. The flange 12
50 fits about the strip 14 and prevents outward re-
traction of the rim, so that the rim firmly and
effectively is secured to the body member without
the necessity of employing brads, staples or
stitches, or of crimping or otherwise positively
55 engaging the rim with the body member. Cus-
tomarily, the body member of the container will
be composed of a flexible fibrous material such
as paperboard.

The mechanism for erecting the carton is
mounted on a framework 15, as shown in Fig. 1. 60

The frame includes an upper platform 16 which may be mounted in tilted relation to facilitate the insertion of containers in the manner to be described hereinafter. In the center of platform 16 is downwardly depending cylinder portion 17 having a lower opening through which extends the shaft 18. The top of shaft 18 supports a conical shaped member 19 and between the base of this member and the base of the cylinder portion 17 is a compression spring 20 which tends to maintain the conical plunger 19 in upwardly raised position.

Shaft 18 is pivotally attached to a downwardly depending lever 21, the lower end of which is secured to intermediate portion of foot lever 22. One end of lever 22 is pivotally attached to the frame structure as shown at 23 and the other end of the member 22 has a foot pedal 24. It will be seen that by depression of the foot lever 24 the rod 18 and plunger 19 may be drawn downwardly.

Mounted on top of the platform 16 is a funnel-like body portion positioning member consisting of divided sections 25. The smallest diameter 25 of the positioning member is substantially equal to the outside diameter of the container 13 exclusive of the strip 14. The sections 25 are funnel shaped and taper downwardly and inwardly, as shown in Fig. 4. Adjacent the lower portion 30 of the inside of the members 25 is a channel portion having an overhanging ridge 26 constituting the most restricted portion thereof and being of substantially the same diameter as the outside diameter of the body portion 13. The ridge 26 is at a height above the platform 16 sufficient to receive the metallic rim 10, and the vertical wall 27 is of substantially the same height and diameter as the outside of the rim 10. More particularly, the cut-away portion adjacent the base of the body portion receiving member is of such size as to receive the metallic rim 10 and to position it for assembly with the fibre container. In this position the projection 26 just overhangs the flange 12 of the rim member. The 40 body portion receiving member consists of two split sections 25 having backwardly extending hinge portions pivoted to a vertical pin as shown at 28 and supported by a bracket 29 secured to the platform. Each of the sections 25 is 45 drilled adjacent the hinge 28 to provide contiguous openings 30 into which is inserted an expansion spring 31. The expansion spring 31 tends to spread the sections 25 apart and stops 32 are mounted on the platform to limit their 55 outer movement.

To the jaw of one of the sections 25 is mounted a catch 32 which is pivoted at 33. A spring 34 presses a rear extension of the catch upwardly, thereby biasing the hook portion 35 in downward position. The jaw of the other section 25 is provided with a projection 36 over which the hook 35 of catch 32 is engaged to lock the sections 25 in closed position as shown in Fig. 3. A front extension 37 on the hook 35 overrides 65 an upwardly extending plunger 38 which passes through the platform 16 in the manner shown in Fig. 3. The lower end of plunger 38 is provided with a pin 39 which engages a slot 40 in a lever 41. An intermediate portion of the lever 70 41 is pivotally attached as shown at 42 to a downward extension 43 of the frame 15. The other end of lever 41 has a slot 44 engaging a pin 45 on the lever 21. It will be seen that upon depressing the foot pedal 24 the pin 45 causes one 75 end of the lever 41 to be depressed and the other

end of the lever to be raised, thereby pushing the plunger 38 upwardly and releasing the hook 35 from engagement with the projection 36. The jaws of the member 25 thereupon are spread apart by spring 31. When so spread apart, it 5 is possible to place a rim member between the jaws, the latter thereafter being manually closed by contracting the jaws and engaging the hook 35 with the projection 36, the pedal 24 being returned to its normal upward position to permit 10 engagement of the catch mechanism.

The conical portion of the member 19 extends upwardly above the platform 16 and as shown in Fig. 5 is surrounded by four expansion sections 46. The sections 46 have central surfaces shaped 15 to fit smoothly and closely about the conical member 19 so that movement of the plunger 19 upwardly will cause the expansion members to be moved outwardly in a horizontal direction into the position shown in Figs. 4 and 5. Each 20 of the expansion members 46 is provided with a depressed portion 47 which provides a shelf 48. Extending from the shelf 48 is an elongated slot 49 which passes through the expansion member. Positioned on the shelf 48 is an elongated washer 25 50 which is shorter than the depressed portion 47. The bolts 51 extend through washers 50 and are secured to the member 16 as shown in Fig. 4, suitable spacers 52 being provided between the washers 50 and the platform 16 so that the 30 bolts cannot clamp the expansion members. That is, the fit between the washer 50 and the shelf 48 is sufficiently loose to allow for the expansion and retraction of the expansion units. As shown in Fig. 5, the spacer units 52 are of a 35 diameter substantially equal to the width of slots 49, so that movement of the expansion units is guided thereby.

Each of the expansion units is provided with an arcuate slot 53, the slots in the various expansion units being in registry. A coil spring 54 is mounted in the slots 53 and causes the expansion units to return to their normal adjacent and unexpanded position when the plunger 19 is moved downwardly.

The outer surfaces 55 of the expansion units 46 slope downwardly and outwardly from their upper surface to a point spaced above the platform 16 a distance substantially equal to the height of the channel portion 11. The outer surface 55 is 50 undercut at this height so that when the plunger 19 is in its upraised position and the units 46 are expanded, the outer surfaces 55 have a projection 56 overriding the upper edge of the channel member 11 as shown in Figs. 4, 6 and 7. 55

In the operation of the device the jaw sections 25 are released as by pressing down on the pedal 24. These jaw sections spread apart and a metallic rim is inserted therebetween. The spring 20 causes levers 18 and 21 to be raised upwardly 60 after the temporary depression of pedal 24 and expansion units 46 are pressed outwardly to the positions shown in Figs. 6 and 7. In this position the members 25 constitute a body portion guiding device having downwardly and inwardly 65 sloping walls terminating just above the top of the flange 12. The fiber body portion of the container to be assembled with the rim has an outside diameter substantially equal to the smallest inside diameter of the guide member 25 adjacent 70 the projection 26 and as the body portion is pressed downwardly within the guide member 25 the projection 14 is contracted as shown in Fig. 6. The body portion of the container is sufficiently 75 flexible to be reduced in its diameter and the end 75

of the body portion and the projection 14 are pressed inwardly beyond the ledge 12. Continued downward movement of the body portion of the container causes the end of the body portion to 5 strike the downwardly and outwardly extending surfaces of the expansion units 46 as shown in Fig. 7. The ends of these members then are turned outwardly and upon continued downward movement of the container are pressed into the 10 channel 11. As the leading edges of the container and strip 14 pass into the channel member 11 and are positioned adjacent the lower portion thereof the other edge of the strip 14 passes beneath the ridge 12 and due to the resiliency of the 15 container the strip 14 snaps outwardly to the position shown in Fig. 8, thereby completing the assembly of the rim and body member. It will be seen that the combination of the upper inwardly sloping guide member and the lower outwardly sloping guide member causes the end of the 20 container to be depressed inwardly around the ledge 12 and outwardly around and into the channel member 11. After the rim and container have been assembled as shown in Fig. 8 the ledge 12 prevents relative outward movement 25 between the rim and the body portion of the container and the channel member 11 prevents relative inward movement and relative lateral movement between the channel member and the body portion of the container, thereby producing an 30 effective interlock between the rim and container without the necessity for crimping, stapling or otherwise securing the two elements together.

After completion of the assembly in the manner described the lever 24 is depressed, thereby causing the guide members 25 to spring outwardly into the position shown in dotted lines in Fig. 2, the expansion members 46 being contracted to 35 permit release of the container and rim as shown in Fig. 8. After removal of the container and rim, another rim is inserted over the expansion joints 46 and the cycle of assembly is repeated with another body portion.

It will be evident that the structure specifically described herein for purposes of explanation may be changed in many respects without departing from the scope of the invention as defined in the appended claims.

I claim:

1. In a device of the type described, means for positioning a rim member, means positioned above said rim member for flexing an edge of a container inwardly past one portion of the rim, and means positioned below and inwardly of said flexing means for thereafter expanding said edge outwardly past another portion of said rim.

2. In a device for assembling a fibrous container having an enlarged portion adjacent the edge thereof with a rim member having a ledge for engaging said enlarged portion and a channel for receiving the end of said container, means for positioning a rim member, means positioned above the ledge of said rim for flexing the end of said container and said enlarged portion inwardly past said ledge, and means positioned below and inwardly of said last named means for thereafter flexing the end of said container outwardly into said channel member.

3. In a device for assembling a fibrous container having an enlarged portion adjacent the edge thereof with a rim member having a ledge for engaging said enlarged portion and a channel for receiving the end of said container, an outwardly movable guide member having down-

wardly and inwardly sloping walls of sufficiently small diameter to flex the container inwardly, and an inner expandable guide member positioned below said first named guide member.

4. In a device for assembling a fibrous container having an enlarged portion adjacent the edge thereof with a rim member having a ledge for engaging said enlarged portion and a channel for receiving the end of said container, an outwardly movable guide member having downwardly and inwardly sloping walls of smaller diameter than the outside diameter of said rim for flexing said container inwardly beyond said ledge, and an inner expandable guide member positioned below said first named guide member and extending 10 over the edge of said channel to flex said container outwardly into said channel, said guide members being cut away to receive a rim adjacent the lower portion thereof.

5. In a device for assembling a fibrous container having an enlarged portion adjacent the edge thereof with a rim member having a ledge for engaging said enlarged portion and a channel for receiving the end of said container, means for positioning a rim member including a guide portion for flexing the end of a container inwardly beyond said ledge, said guide portion being movably positioned so as to release said rim member for assembly with the container, and an inner guide member for expanding the edge of said 20 container into the channel member of said rim, said inner guide member being retractable to permit release of said rim.

6. In a device for assembling a fibrous container having an enlarged portion adjacent the edge thereof with a rim member having a ledge for engaging said enlarged portion and a channel for receiving the end of said container, comprising split outer guide jaws having inwardly and downwardly extending portions terminating in 35 an undercut for receipt of the upper ledge of a rim, and an inner guide member having downwardly and outwardly extending walls terminating in an undercut for receiving the channel portion of a rim member, said inner guide member being composed of a plurality of expandable and retractable portions.

7. A device for assembling a fibrous container having an enlarged portion adjacent the edge thereof with a rim member having a ledge for engaging said enlarged portion and a channel for receiving the end of said container, comprising inwardly movable means positioned above the ledge portion of one of said rim members for flexing the edge of a container inwardly beyond the 50 ledge of the rim, and inwardly and outwardly movable means positioned below and inwardly of said last named means for thereafter flexing the edge of said container outwardly.

8. In a device for assembling a fibrous container having an enlarged portion adjacent the edge thereof with a rim member having a ledge for engaging said enlarged portion and a channel for receiving the end of said container, comprising inwardly movable means positioned above 60 said rim member for flexing the end of the container inwardly upon relative motion between a container and a rim and outwardly movable means positioned below and inwardly of said last named means for thereafter flexing the end of 65 the container outwardly upon continued relative movement between the container and a rim.

HENRY K. POWELL.
